Attorney

UNITED STATES PATENT OFFICE.

ROBERT F. METCALFE, OF ERIE, PENNSYLVANIA, ASSIGNOR, BY MESNE ASSIGNMENTS, TO SOCONY BURNER CORPORATION, OF WILMINGTON, DELAWARE, A CORPORATION OF DELAWARE.

FUEL BURNER.

Application filed August 30, 1922. Serial No. 585,219.

This invention is designed to provide a mounting for fuel furnaces, particularly such burners as are used with domestic furnaces. Such burners have to be adjusted to 5 different kinds of furnaces and different heights of furnaces. One of the purposes of the invention is to make an adjustable mounting which will carry the burner so that it may be placed at the proper height 10 in the furnace without any particular changes or attachments to the furnace. Another objection to such burners is the noise. One of the purposes of the invention is to reduce the noise incident to the operation of 15 the burner. Features of the invention will appear from the specification and claim.

The invention is illustrated in the accompanying drawings as follows:—

Fig. 1 shows a rear view of the burner. 20 Fig. 2 a section of the combustion chamber and its mounting. 1 marks the combustion chamber, 2 a motor, 3 a fan driven by the motor and delivering air to the combustion chamber, 4 a pump 25 driven by the motor and delivering atomizing air and 5 a fuel supply which is delivered to the atomizer. These may be of any ordinary construction. The burner is supported on posts 6, three of these being supplied 30 so as to give a stable foundation whatever the nature of the platform or floor on which the burner is mounted. These are provided with the feet 7 which are placed on extensions 8 against shoulders 9 on the posts 6. 35 The feet 7 have the sockets 10 in which rubber pads 11 are forced.

A bracket 12 is arranged under the combustion chamber at the front end of the burner. This bracket has a socket 12^a for

receiving a post 6 and the post is kept in adjustment at any desired height by a set screw 13. A bracket 14 having an opening through it is secured to the pump 4 and a post 6 extends through this bracket and is adapted to slide therein and is locked in 45 any desired adjustment by a set screw 15. A similar bracket 16 is secured to the motor and has an opening through it through which a post 6 extends and is free to slide therein, the post being locked in any desired 50 adjustment by the set screw 17.

The burner and its operating parts, it will be noted, form a single unit and the three posts form an adjustable mounting for this unit, the rubber pad forming sound dead- 55 eners which reduce the sound very materially in the use of the burner.

What I claim as new is:—

In a fuel burner, the combination of a combustion chamber horizontally arranged 60 and designed to deliver its flame horizontally from its inner end; a motor arranged at its outer end; air delivery devices delivering air to the chamber driven by the motor; means for supplying fuel to the chamber, said chamber, motor, devices and means being rigidly connected as a unit; three supports for said unit, two of said supports being arranged at the outer end and one of 65 said supports in front of the center of gravity of the device; and means independently adjusting said supports to vary the height 70 of the unit and level the unit longitudinally and transversely.

In testimony whereof I have hereunto set 75 my hand.

ROBERT F. METCALFE.
